M. M. GRAY.
MACHINE FOR MAKING RAILWAY CHAIRS.

No. 10,571.

Patented Feb. 28, 1854.

UNITED STATES PATENT OFFICE.

MICHAEL M. GRAY, OF PHILADELPHIA, PENNSYLVANIA.

RAILROAD-CHAIR MACHINE.

Specification of Letters Patent No. 10,571, dated February 28, 1854.

To all whom it may concern:

Be it known that I, MICHAEL M. GRAY, of Philadelphia, in the county of Philadelphia, State of Pennsylvania, have invented a new 5 and useful Improvement in Machines for Making Railway-Chairs; and I do hereby declare that the following is a full, clear, and exact description thereof, reference being had to the accompanying drawings and to 10 the letters of reference marked thereon.

The nature of my invention consists in the manner of causing a series of punches, knives, and dies and a former and its base to operate upon a heated plate of malleable 15 iron so as to pierce, cut, and compress, the same into the form of a railway chair in a better manner than before known.

In order to enable others skilled in the art to make and use my invention I will proceed 20 to describe the manner of its construction and operation.

In the accompanying drawing Figures 1 and 2 are a sectional elevation and plan of the improved machine complete, and drawn 25 to a scale of three quarters of an inch to a foot. The remaining figures, 3, 4, 5, 6, 7, and 8 are enlarged views of those parts of the machine to which my invention more particularly relates, Fig. 3 being a face view 30 of the part against which the heated plate is placed preparatory to being operated upon by the punches, knives, and dies. Fig. 4 is a sectional plan of the same, showing the piece of heated iron inserted in the recess. 35 Fig. 5, another view of the same in which the punches, knives and dies have been brought to act upon the heated iron; Fig. 6, another sectional view on the line *a, b*, showing the sliding form more distinctly, and 40 Figs. 7 and 8 are perspective views of the piece of iron before it has been operated upon by the machine and afterward, when it has assumed the form of a railway-chair.

The same letters of reference allude to 45 similar parts throughout the several views.

Description of machine.—Referring to Figs. 1 and 2 A is the framework of the machine, consisting of two sides, a base and projection for receiving the die block, all 50 cast in one piece. In the side of the frame are two bearings for the reception of eccentric shaft B and driving the shaft C; on the former is secured the toothed wheel D which gears into the pinion E on the shaft 55 C which is caused to revolve by the shaft and pulleys F.

On the shaft B is secured the eccentric on which works the rod H; the other end of this rod works on a pin attached to the sliding ram I which is guided by flanges cast 60 on the sides of the frame A. To the end of the ram I is secured the block M, to which are attached by any convenient means the knives S and punches R. On the shaft B is keyed another cam J; this as the shaft revolves actuates the lever K whose fulcrum is on the pin L passing through the sides of the frame A. The other end of the lever K is attached by a joint to the rod Q on which is the sliding former U. The upper portion 70 of the rod as well as the sliding former is guided by the die block N which is securely attached to the projecting portion of the frame A. The particular form of the die block N, and the dies and former which it contains will be best understood on reference to the enlarged views Figs. 3, 4, 5, and 6. In Fig. 3 it will be observed that the block is furnished with four lugs two on each side by means of which it is secured to the projecting portion of the frame. Into the face of each side of the block are inserted steel 80 plates perforated with square holes for the reception of the punches R on the block M, to which are also attached the knives S the 85 latter as the ram advances cut through the plate and pass into the space between the dies P and sides of the block N, and the punches and knives hold the heated plate steady. The dies P are actuated by means of 90 the levers O (Fig. 2) which have fulcrums on studs attached to the side of the frame A. One end of the levers O bears against the cams V which are secured to the ends of the shaft B in such a manner as to act simultaneously. The other ends of the levers O bear against the ends of the sliding dies P 95 between which and the frame intervene spiral springs.

It will be easily seen that as the shaft B 100 revolves the levers O through the action of the cams V will cause the sliding dies to be forced toward the sliding former U; as the cams however recede from the ends of the levers, the elasticity of the spiral springs 105 will cause the dies to resume their former position.

Action of the machine.—Having now described the several parts of the machine I will proceed to show how the same may be 110 carried into effect.

Let us now suppose the machine to be in

operation and the ram in the position shown in Fig. 1, that is at the end of the outward stroke; a piece of heated iron of the required dimensions is now placed in the 5 recess formed above the perforated steel plates on the block N; the sides of the recess and a flange on the spindle Q acting as guides to insure the piece assuming a proper position. The ram now advancing 10 toward the heated plate, the latter will in the first instance be cut by the knives S which will also partly bend the lips downward as shown in Fig. 4; the plate will then by the continued onward movement of the 15 ram be pierced with holes by the punches R the plate remaining stationary on the former and block and the pieces of iron thus punched out passing into a space behind the steel plates and thence into the space be- 20 low the box. The cams on the end of the shaft B now act suddenly and simultaneously on the lever O which will force the sliding dies P toward the former U, the dies as well as the former being so shaped 25 as to give the requisite shape to the lips or that portion of the plate which has been cut and bent partially down by the knives. The levers O being now suddenly released from the projecting parts of the cams V the 30 dies P will, through the action of the spiral springs, be freed from contact with the heated iron and resume their former position. The ram through the action of the eccentric now commences its backward 35 stroke and thus withdraws the knives and punches, and at the same time the cam J operating upon the lever K, the sliding former U will be brought downward and likewise released from the heated iron which 40 has now assumed the form of a railway chair. The latter will still continue to adhere to the knives and punches. In order to free it from contact with these, I make use of the stripper plate which works 45 loosely on a pin attached to the end of the ram. The knives and punches likewise move freely in spaces cut in the stripper plate, as they however continue to recede along with the ram the stripper plate will 50 catch the ends of the frame A and thus strip the chain from the knives and punches, it will now drop into the space below. The machine is now in such a position as to repeat the operations on another heater plate. 55 I am aware that machines have been invented by Winslow and Snyder having a sliding former traveling up and down with flat faced cutters or square faced punches in a ram to cut the lips of the chair; the 60 sliding former and flat faced cutters pressing the ears and main body of the heated plate of metal down on to a bed beneath, leaving the lips to curl up by the resistance

of the tops of the dies as the heated plate passed down, and when down the dies 65 swedged the lips over the top of the sliding former, and I do not claim this manner of arrangement nor action nor any combination involved in this machinery my invention being an improvement upon this machine. Also I am aware that a hand former has been used; and also that punches have been set in the base on to which the plate of metal was to be so forced down with the view of also punching the spike holes in the 70 plate at the same operation and I do not claim this combination or arrangement, and further I do not claim the stripper plate to strip the cut and formed metal from the receding knives and punches as it has been 75 before used in a similar manner for an analogous purpose in cracker and iron punching machines.

To distinguish my improvement, I make my machine with the sliding former similar in shape to a vertical cross section of the rail, so as to have a base, to rest and slide on the bed plate and having a horizontal motion and no other, that is perpendicular to the motion of the ram, and thus sliding 85 and resting on this solid base, and receiving the plate of heated iron on its top; and the plate remains stationary in the machine except the lips alone which are being cut and curled and swedged down into shape, being 90 held steady on the former and base by the knives and punches, and finally the face of the ram or stripper plate during the operation; and the former keeps firm and cool in contact with the bed plate. And in the 95 operation of cutting with the vertical plate knives, the cut is made deeper than the base of the lips to make them form up true at the bend and not tear or break where they fold on the former. By these means all the 100 chairs are cut, punched and shaped true and uniformly with economy and expedition and the best quality of iron is not required to make them without breaking at the bends; red short iron will answer in this 105 machine.

What I claim is—

Operating the sliding former or mandrel upon the base or pedestal to keep it firm and cool, and cutting, curling and swaging 115 the plates of metal to be formed into the chairs while in a stationary position and at a proper heat on the top of this sliding former instantly in the manner and by the means as described, to produce the chairs uniform in shape, and cheaply of low-priced 120 or red short iron without fracture.

MICHAEL M. GRAY.
